UNITED STATES PATENT OFFICE.

EUGENE L. MESSLER, OF PITTSBURG, PENNSYLVANIA.

GAS-RELIEF VALVE FOR BLAST-FURNACES.

No. 813,442.

Specification of Letters Patent.

Patented Feb. 27, 1906.

Application filed November 9, 1904. Serial No. 231,998.

To all whom it may concern:

Be it known that I, EUGENE L. MESSLER, of the city of Pittsburg, county of Allegheny, and State of Pennsylvania, have invented a new and useful Improvement in Gas-Relief Valves for Blast-Furnaces, of which the following is a full, clear, and exact description, reference being had to the accompanying drawings, forming part of this specification, in which—

Figure 1 is a side elevation of the bleeder-stack leading from the stack of the furnace, the stack being provided with my improved relief-valve. Fig. 2 is a vertical sectional view of the upper portion of the valve and the upper portion of the bleeder-stack, and Fig. 3 is a plan view of the same.

Like symbols of reference indicate like parts wherever they occur.

The object of my invention is to provide a gas-relief valve for blast-furnaces which shall permit the relief or escape of the gas when it is so desired and shall under other circumstances so close the bleeder-stack as to prevent the escape of dirt and gases. In blast-furnace practice it is customary to conduct the gases produced by combustion of fuel in a blast-furnace stack from the stack by a suitable bleeder-conduit to the boilers or other place where these gases are used as fuel. When, however, the gases are not being so used or when there is an excessive supply of such gases, it is necessary that the gases may be allowed to escape. Heretofore the valve which has controlled the retention and escape of these gases has been of such construction as to open upwardly from its seat and permit of the leakage of gases and the escape of ore-dust and other dirt during the charging of the blast-furnace, and this leakage and escape of dirt and dust has been in certain cases so great as to cause excessive annoyance to the community within which the blast-furnace was situate and to constitute a nuisance.

My invention consists in an improved valve located in the bleeder-conduit and adapted to perfectly seal the escape-opening through which the furnace is relieved by permitting the escape of gas, and to be easily opened or closed whenever it becomes desirable or necessary so to do.

I will now describe my invention so that others skilled in the art to which it appertains may manufacture and use the same.

In the drawings, 2 represents the stack of the furnace; 3, the bleeder-conduit opening from the top of the furnace-stack and leading vertically to a point above the same. At the top of the bleeder-conduit 3 is a cover 4, provided with a valve-seat 5, which is bolted around an opening in the cover. Situate at the top of the conduit 3 and adapted to seat on its upward movement against the valve-seat 5 is a bell-shaped valve 6. Extending from the apex of the valve 6 is a short link 7, pivoted to the valve and also pivoted to the lever-arm 8, which arm is pivoted to the standard 9. Extending from the two ends of the lever-arm 8 are the chains 10, which extend downwardly to the point of access by the workmen and by means of which the valve 6 is caused to open or close to permit the relief of the stack by the escape of gases through the valve-opening or to confine the gases, dirt, and ore-dust within the bleeder-conduit 3 during the period the gas is being used under the boilers and during the period when the ore-dust would be liable to escape in injurious quantities through the valve-opening.

The advantages of my improvement will be appreciated by those skilled in the art. No matter how great the pressure of gas may be within the furnace and within the bleeder-conduit 3 it serves merely to more tightly press the valve 6 against the seat 5. At the same time the valve is easily and quickly operated to permit the relief of the furnace by the escape of the gases.

Having thus described my invention, what I claim, and desire to secure by Letters Patent, is—

1. In combination, a bleeder-conduit leading from the upper portion of a blast-furnace, a valve-seat arranged in said conduit, and a valve adapted to move upwardly toward its seat in the direction of the pressure of the gases in the bleeder-conduit, substantially as described.

2. In combination, a bleeder-conduit leading from the upper portion of a blast-furnace, a valve-seat at the top of said conduit, a bell-valve adapted to seat upwardly against said valve-seat in the direction of the pressure of the gases in the bleeder-conduit, and an operating-lever connected to the valve, substantially as described.

3. In combination, a bleeder-conduit leading from the upper portion of a blast-furnace,

a valve-seat at the top of said conduit, a bell-valve adapted to seat upwardly against said valve-seat in the direction of the pressure of the gases in the bleeder-conduit, a standard at one side of the valve, a lever pivoted to the valve and to said standard and extending beyond the valve at one end and beyond the standard at the other end, and operating-chains for opening and closing the valve con-

nected to the ends of said lever, substantially as described.

In testimony whereof I have hereunto set my hand.

EUGENE L. MESSLER.
